DIE

Thomas A. Bowers, Boston, Mass., assignor to
 Power Research Corporation, Boston, Mass.,
 a corporation of Massachusetts

Application January 2, 1937, Serial No. 118,864

8 Claims. (CL. 78—18)

This invention relates to dies and more particularly to forming dies for use in the manufacture of packing and piston rings formed from a plurality of metal pieces. An example of one type of piston ring is disclosed in my co-pending application, Ser. No. 733,243, filed June 30, 1934, for Piston ring material. The present application is a continuation in part of my now pending application for Dies, Ser. No. 20,738, filed March 10, 1935.

The principal object of my invention, therefore, is an improved die structure.

Another object is a die structure comprising means for reducing the circumference of a ring of material composed of loosely compacted folds or sheaves of metal.

Another object is a device of the character described in which means are provided for eliminating buckling of the ring material while being compressed.

Another object is a tapered forming structure for shaping the tops and sides of a fabricated packing ring.

Another object is the provision of means in a die for flowing or otherwise reacting on metal for a fabricated piston ring.

Other objects and novel features forming a part of the invention will appear as the description progresses.

30 In the drawings embodying my invention—

Fig. 1 is a vertical symmetrical cross section of the complete die in a loading position.

Fig. 2 is a fragmentary vertical cross section of the die in a loading position.

35 Fig. 3 illustrates a fragmentary cross section similar to Fig. 1 with the head of the die dropped down to a contact position.

Fig. 4 is a view similar to Figs. 1 and 2 showing the die in a finally closed position.

40 Fig. 5 is a view in fragmentary cross section similar to Figs. 1-3 inclusive and illustrating the die raised after the completion of an operation.

Fig. 6 is a fragmentary vertical cross section of a modified type of die construction illustrating plate holding means in elevation and indicating the reduction of a ring from one die size to another smaller die size.

Fig. 7 is a view similar to Fig. 6 and showing the complete die in a contact position.

50 Fig. 8 is a plan cross section taken on the line 8—8 of Fig. 7.

Fig. 9 is a cross section of the plate holding means taken on the line 9—9 of Fig. 7 and further 55 illustrates the plate holding means in a lowered

position relative to the ring diameters also shown in cross section.

Fig. 10 is a view similar to Fig. 7 illustrating the further reducing of the ring treated in Fig. 8 in a smaller die.

Fig. 11 is a detail view in perspective and partial cross section of the adapter plate illustrating a locking means.

Referring more in detail to the drawings, Figs. 1-5 inclusive illustrate one form of shouldered 10 anvil, die head and tapered die sleeve. Figs. 6-11 inclusive illustrate a somewhat similar tapered die structure provided with alternate locking plate structure to take the place of an anvil and die head.

15 The material to be reacted on by these structures may comprise a length of reversely folded metal ribbon of circular formation or a plurality of strips or metal spacers held together in a substantially circular body by any suitable means. 20 With reference to the die illustrated in Figs. 1-5 inclusive, 11 indicates a die sleeve in which the work is effected, being constructed with a definite taper for the length of the sleeve and having its inner surface 12 highly polished to impart a finish 25 to piston ring 13. The die sleeve 11 will be supported by some suitable base such as a heavy bolster plate 9 and slidably disposed within the die sleeve has been provided an anvil 14 whose periphery will be of a size to slidably engage in the 30 smaller dimension of the die sleeve 11. Anvil 14 is recessed at its top portion to provide a shoulder 15 which is adapted to receive the piston ring 13 while the latter is of a circular size large enough to extend over the shoulder and against the die 35 sleeve 11.

16 indicates a die head comprising a plate construction with an annular flange 17 which is provided for the purpose of attachment to a press head by means of conventional dogs or similar 40 holding means.

Die head 16 is recessed at 18 to receive a punch member 19 secured thereto by means of bolts 20. The bottom side of punch 19 is recessed at 21 to form an annular punch ring 22, the outer circumference of which, subject to clearance, is of the same diameter as the lower inner periphery of the die sleeve 11 and shouldered portion of anvil 14 over which the punch ring is adapted to seat on the piston ring 13. A rod 23 is anchored in the 45 top of the press head, not shown, and extends downwardly through the center of the die head, the punch and the anvil, being provided on its lower end with a head 10a.

Bolster plate 9 has an opening 11a for receiv-

ing the head 10a, which is also recessed in the anvil 14 at 12a. 13a is a leather ring for maintaining the anvil 14 in a floating position in the die sleeve 11.

5 In operation the piston ring 13, partially closed, is placed in the die as indicated in Fig. 2. The die punch 19 is brought down into contact with the piston ring material 13 as shown in Fig. 3. It will be noted that the upper portion of the
10 inner periphery of the die sleeve is tapered upwardly and outwardly so that the piston ring material being in an expanded condition extends outwardly to engage the upper surface of die sleeve while the inner periphery of the ring is
15 spread away from the shoulder of the anvil.

15 It is to be noted that when the die punch ring
is contacting with the piston ring material, be-
fore the die has been fully closed, I have pro-
vided for there being a clearance space between
20 the upper surface of the anvil and the central
surface of the punch bottom. As the die punch
is pressed down in contact with the piston ring
material the tapered surface of the piston ring
or die sleeve compresses the piston ring ma-
terial radially until it conforms to the lower inner
25 periphery of the die sleeve, at which time the
inner periphery of the piston ring material be-
comes tightly seated around the shoulder of the
anvil. As the die reaches its final position, the
30 clearance space between the punch and anvil is
entirely closed up.

During this operation the piston ring material has changed in character and has now taken a form in which each segment of metal is slightly keystone shaped throughout.

The action of this die may be said to be two-fold as it to some extent radially compresses and then at the end of the stroke delivers a blow which finally forms the ring. This latter action is very important and calls for the somewhat special structure shown.

For instance, the pressure required to force anvil 14 thru the die sleeve 11, up until the anvil bottoms on the bolster plate, may be relatively small as possibly a half ton. However, as soon as the anvil bottoms on the bolster plate, a very large force acts almost instantaneously like a blow. The pressure at this point may be 150 to 300 tons per square inch on the ring material which is formed and set into the desired shape and all rounded portions are eliminated. To withstand such pressure, the elements must be made very strong and must balance one another as otherwise the die may burst. Also in returning the punch and anvil a very large pressure is required which necessitates the head construction 10a for gripping the anvil. By the utilization of the disclosed structure the important work done on the ring at the end of the stroke may be effected.

Figs. 6-11 inclusively relate to a structure combined with tapered die sleeves for reacting on a ring made up of folds of reversely bent ribbon or a plurality of metal strips secured together in some desirable manner. It is desirable to provide a substantially large number of such pieces with their corresponding interstices. To effect such a result, it may be necessary to start with a ring considerably larger in circumference than the ultimate finished ring. On this account it may be advantageous to reduce the ring either by a single die sleeve or gradually in successively smaller die sleeves.

Also it may be desired to apply finishing action to the periphery of the piston ring material.

with less consideration being given to flattening the tops and bottoms of the ring under pressure. When this is done the anvil means is never bottomed to develop a large pressure as illustrated in Figs. 1-5 inclusive. The anvil means are continuously floating in the die sleeves which are themselves modified to present a uniform taper throughout their length.

If the ring is reduced in one operation, the retaining means for securing the ring within the die sleeve must be of a compressible design to allow for its passage through an extended die sleeve length. Various expandible constructions known in the art may be employed for such a purpose. 15

The structure about to be described illustrates the use of successive smaller die sleeve units with holding means designed to carry the piston ring material through the tapered die section without any compressible construction being utilized. 20

25 indicates a base for receiving a die sleeve as 26 which may be shouldered at 27 to seat on base 25. The base 25 is annually recessed at 28 to receive therethrough one side of a locking plate unit generally indicated by the arrow 29 which is compressibly and slidably mounted by some convenient means such as post 30 and spring 31 passing through sleeve 32. A collar member 33 is engaged adjacent sleeve 32 having downwardly extending flanges 34 and upwardly extending flanges 35. Located adjacent collar 33 is provided a retaining ring 36 upon which is fitted an adapter plate 37. The collar 33 is internally threaded at 38 to receive locking end portion 39 threaded at 40 of a second locking plate unit generally referred to by the arrow 41. The second or upper locking plate unit 41 is provided with a body portion or post 42 secured to a press head 43 by means of a pin 44. 45 indicates a retaining ring securely adjacent body portion 42 being somewhat similar to retaining ring 36 already described relative to plate unit 29. Also adjacent retaining ring 45 is an adapter plate 46 similar to adapter plate 37.

The retaining ring 45 and adapter plate 46 may be locked into place by any suitable arrangement such as for instance a pin or stud 47 on body portion 42 which is adapted to vertically engage through groove 48 and lock in groove 49, these grooves being more clearly shown in Fig. 11.

In Fig. 6 I have illustrated in vertical cross section two die sleeve sections 24 and 26 seated one within the other with the locking plate units 41 and 29 out of engagement with a piston ring 50. While the locking plate unit 29 has been shown in Fig. 6 in a raised position relative to base 25, it should be understood that it may be depressed and locked in a lower position by means of a handle 51 and holding member 52 for purposes of removal of retaining ring 36 and adapter plate 37.

The plate unit 41 will have some convenient means associated with the head 43 for its being lowered into engagement with the piston ring 50 at any point in the die sleeve 24.

The ring 50 may be entered at the top of die ring 24 by an convenient means as for instance being slid out of a sleeve of the same diameter as the top of die ring 24.

In Fig. 7 the plate unit 29 has been shown in a fully assembled state to support and receive ring 50 on adapter plate 37. Likewise, plate assembly 41 is shown lowered into an operative position and the locking end 39 has been screwed

into the threaded portion of collar 33 by turning handle 51.

In the particular operation illustrated in Figs. 6 and 7 the piston ring 50 has been indicated after having been passed thru one die step, that is to say it has been tapered to the extent possible in the die sleeve 24, and is about to be carried through the next successively smaller die, by pressure against the head 43, any suitable type of press being applicable and for convenience not illustrated in the drawings.

It is pointed out that in the use of clamping means for passing a ring of material through a tapered sleeve, some limitations may be encountered. This differs from other situations where a solid circular body might be passed through the tapered sleeve or where clamping action occurring on both the top and bottom sides of a ring body is not necessary.

In passing a ring from the top of a downwardly tapered die of any given diameter at the top, to the bottom of the die where a smaller diameter is present, non-contractible means for supporting the under side of the ring must have a diameter of a size allowing such means to slidably engage in the smaller dimension, and the ring, when at the top of the die, must have a radial width of such value that its inner diameter is less than the diameter of the supporting means as otherwise the supporting means will not be large enough to engage the ring at the top of the die.

Similarly, in passing from one die of a given diameter to a succeeding tapered die of smaller diameter, the difference in dimension between the diameter at the bottom of the first die and the diameter at the bottom of the second die must be less than the radial width of the ring when it is in the bottom of the first die.

This is so for the reason that whenever, as is the case here, a non-contractible supporting means is used, for supporting the under side of a ring to be passed through tapered sleeves, its maximum range of supporting area is limited to the diameter of the bottom of the lower sleeve through which the supporting means must slide. Therefore, while the work might be contracted to almost any degree, in order to provide supporting means which will engage the under side of the ring in the larger diameter, and which will itself slide downward through a smaller diameter, this relation must be preserved.

It should be understood that in operation these die sleeves are made up to rigid specifications so that they are able to effect a definite change in a ring as 50 and with each size of die ring which will be numbered or otherwise indicated, there will be a similarly sized adapter ring likewise numbered in relation thereto. These adapter plates clamp on to the ring while it is being reduced and only inward movement of the ring is possible.

In Figs. 9 and 10 there has been illustrated a die sleeve 53 mounted on a die sleeve 54 of uniformly smaller taper. Fig. 9 illustrates the rearrangement of die 54 mounted on a still smaller die 55 with the ring being held in the lower part of die 54 secured by the locking plate units 41 and 29 and ready to receive further compressing treatment.

For production work it is intended that means may be provided for mechanically removing the die ring containing the piston ring at the end of each operation, that is to say, the ring as it passes from sleeve to sleeve will be treated

by a number of press units. This is, of course, an alternative to constructing the plate units of a compressible character whereby a single long die sleeve length may be utilized.

There are numerous advantages attached to the use of the plate units such as elimination of all tendency in the ring to buckle with its passing through the die sleeve, the simplicity of the engagement with the ring, the flexibility of handling the die units, and the accuracy of work performed in the tapered periphery for any given ring size. The use of the adapters, particularly sized in relation to the corresponding die sleeve, provides a novel, convenient, and expedient means for providing an anvil and punch with this type of die structure.

It is considered that the use of combined adapter plates and die sleeves may be admirably suited for other purposes than treating the particular piston ring material here illustrated. Various changes in proportions, locking means, and the like may be practiced in keeping with the spirit of the present invention.

Having thus described my invention, what I claim is:

1. A radial finishing and shrinking die for use in treating a circular length of a reversely folded metal ribbon comprising a base ring, an anvil member, a die punch, and a punch ring portion formed on the lower extremity of said punch, said base ring having its inner periphery gradually tapered and converging downwardly into a cylindrical portion and adapted to frictionally polish one side of said metal ribbon when downwardly forced thereagainst, said anvil member being annularly shouldered at its upper extremity to receive said ribbon, said punch ring portion adapted to seat against said anvil and slidably engage in the throated portion of said ring and said die punch having an initial clearance between said anvil shoulder and itself corresponding to and for gauging the degree of reduction of said ribbon.

2. An apparatus for circumferentially reducing and forming a piston ring formed from a reversely bent metal ribbon comprising a ring die portion, an anvil movably disposed within said die portion, and a punch adapted to engage over said anvil and secure said ring therebetween, said ring die having its inner periphery uniformly tapered from a greater diameter at the top thereof to a lesser diameter of a size adapted to receive said anvil member, occurring a substantial distance downwardly of said inner die periphery, and a bolster plate located below said die for receiving the base of said anvil member thereon, and a lifting rod member secured through said punch, being slidably received in said anvil member and having a head portion at the lower end thereof recessed in the under side of said anvil.

3. An apparatus for circumferentially reducing and compacting a piston ring formed from reversely bent metal ribbon comprising a ring die portion, said ring die having its inner uniformly tapered from a greater diameter at the top thereof to a lesser diameter, of a size adapted to receive an anvil member at the bottom thereof, an anvil locking plate and punch locking plate for securing said piston ring therebetween, said anvil locking plate and punch locking plate comprising retaining ring and adapter plate elements being sized relative to the circumference of the inner periphery of a respective die at its

smallest dimension in such a manner as to be slidably received thereby.

4. An apparatus for circumferentially reducing a ring formed from reversely bent metal ribbon comprising a ring die portion, said ring die having its inner periphery uniformly tapered from a greater diameter at the top thereof to a lesser diameter of a size adapted to receive supporting means, an anvil locking plate unit comprising the supporting means, and a punch locking plate unit having a threaded locking end adapted to be received in a smaller threaded opening in the said anvil locking plate unit for the purpose of adjustably securing said ring therebetween.

15. An apparatus for circumferentially reducing a ring element comprising a ring die member having a tapered inner periphery, means for engaging said ring element at its upper and lower sides in said die, said means comprising an anvil locking plate unit and a punch locking plate unit received through the bottom and top respectively of the said die, a threaded engaging end extending out of said punch locking plate unit adapted to engage in a similarly threaded opening in said anvil locking plate unit, and pin means for locking the said units together.

6. An apparatus for circumferentially reducing a ring element comprising a ring die member having a tapered inner periphery, anvil means adapted to receive the under side of said ring element in the die and punch means adapted to engage the upper side of the ring element against the anvil means in the die, the diameter of said anvil means and said punch means being of such

dimension as to be received through the bottom of said ring die and said diameters also being greater than the inner diameter of said ring element when the ring element is entered at the top of said die.

7. An apparatus for circumferentially reducing a ring element comprising a ring die member having a tapered inner periphery, anvil means adapted to receive the under side of said ring element in the die and punch means adapted to engage the upper side of the ring element against said anvil means, the difference in dimension between the inner diameter at the top of said die and the inner diameter at the bottom of the die being less than the radial width of the said ring element when at the bottom of the said die.

8. An apparatus for circumferentially reducing a ring element comprising a plurality of ring dies, mounted one above another and having their inner surfaces tapered to form an uninterrupted conically-shaped aperture whereby the said ring element may pass through a uniformly decreasing diameter, anvil means adapted to engage the lower side of said ring element in the die and punch means adapted to engage the ring element at its upper side, and means for clamping the punch means and anvil means together, the diameter of the said anvil means being greater than the inner diameter of the said ring element when the ring is located at the bottom of the first of said dies and said anvil means diameter also being of a size adapted to slidably engage in the bottom of a second successively smaller die.

THOMAS A. BOWERS.
